ATTORNEYS

UNITED STATES PATENT OFFICE

FRANK G. STEINER, OF CHICAGO, ILLINOIS, ASSIGNOR TO STEINER SALES COMPANY,
OF SALT LAKE CITY, UTAH, A CORPORATION OF UTAH

INDIVIDUAL-TOWEL CABINET

Application filed July 2, 1928. Serial No. 289,827.

- My invention relates to that type of individual towel cabinet which comprises a stand or frame adapted to rest upon the floor, having in its upper portion a support where-
5 on the bundle of individual towels is sup-
ported and provided in its lower portion
with a space or chamber wherein the soiled
towels are allowed to fall when released by
the user.
- 10 The primary object of my present invention
is to provide improved means for exerting a
yielding backward pressure on the bundle of
towels and allowing the convenient grasping
of the forward towel of the bundle and its
15 removal to a position where it can be readily
used. In towel cabinets of this type, using
a follower board or plate for exerting a back-
ward pressure on the bundle of towels, it is
usually necessary for the person loading the
20 cabinet to hold the follower or plate in an
outward or withdrawn position with one
hand, while the handle of clean towels is
placed in position in the rear of the follower
with the other hand.
- 25 With my improvement the follower will
be moved to and held in its outermost posi-
tion by foot power, and the attendant will
have both hands free to place the towels in
the cabinet. A further object is to provide a
30 cabinet with a follower that will be positive
and reliable in its operation and in which it
will be practically impossible for the user
of the cabinet to prevent the follower from
maintaining a continuous pressure on the
35 bundle of towels. Pressure on the treadle
will release the towel and permits its con-
venient removal, but as soon as the foot is
removed from the treadle the follower will
automatically assume its working position.
- 40 Other objects of the invention will appear
from the following detailed description.

The invention consists generally in various
constructions and combinations, all as here-
inafter described, and particularly pointed
45 out in the claims.

In the accompanying drawing forming
part of this specification,

Figure 1 is a side elevation partially in sec-
tion of an individual towel cabinet embody-
50 ing my invention;

Figure 2 is a similar view showing a quan-
tity of towels in the cabinet with the follower
thrown forward by the depression of the op-
erating treadle;

Figure 3 is a front elevation of the cabinet; 55
and

Figure 4 is a detail sectional view.

In the drawing, 2 represents the rear up-
right rails of the frame having their lower
ends adapted to rest upon the floor and form 60
rear supporting legs; 3 represents the for-
ward legs having upwardly and rearwardly
inclined braces 4 which are secured to the
legs 2. Suitable braces 5 are provided at the
bottom between the front and rear legs and 65
above the legs 3 the forward and rear portions
of the rails are connected by plates 6. A plate
7 surmounts the legs or rails 6 and has a
socket 8 therein adapted to receive a plate 9
that is mounted on the end of a rod 10. This 70
rod is adapted to pass through eyelets or
grommets in the individual towel 11 and flex-
ible means such as a chain 12 connects the
forward end of the rod 10 with a lock device
13 which prevents any unauthorized or mal- 75
icious person from removing the towels and the
hanger or support therefor from the cabinet.
This lock device 13 is mounted on a cross rod
14 which serves as a connecting means be-
tween the rear legs of the cabinet. Bars 15 80
are pivoted at 16 on the vertical flanges of the
braces 4 and provided with a follower plate
17. This plate has studs 17' intermediate its
upper and lower edges and these studs fit
loosely in holes 17" provided in the bars 15 85
and allow the follower to swing freely and
seat itself against the bundle of towels. A
rod 18 connects the upper portions of the bars
15 for holding them in parallel relation and
the pivot at 16 permits the bars to swing 90
freely back and forth preferably in slots 19
provided in the horizontal flanges of the
braces 4, the walls of the slots forming guides
for the bars. A U shaped treadle 20 is piv-
oted at 21 at the rear of the machine and has 95
bars 22 connecting its middle portion with
pairs of toggle links 23 and 24 on each side
of the cabinet, the upper ends of the bars be-
ing joined to the links at their point of inter-
section, having a common pivot with them, 100

and as the bars are raised and lowered by the operation of the treadle, the links 23 and 24 will form toggles, opening up to swing the upper ends of the bars 15 forwardly against the tension of the coil springs 25. The bars 22 preferably move vertically in slots provided in the horizontal flanges of the braces 5. A shield 26 is preferably provided wherein the springs 25 and the links 23 and 24 are mounted, the former pivoted at 27 on the braces 4. Normally the tension of the springs 25 will draw the lower portion of the bars 15 forwardly and press the follower plate against the bundle of towels that is supported in the upper portion of the cabinet, and tend to hold the follower against the surface of the bundle with a yielding pressure. An individual towel when desired for use, can be drawn out between the towel supply and the yielding follower.

With this device the attendant will only need to depress the treadle and thereby the follower will be moved out away from the bundle of towels. Normally the parts will be in the position as substantially shown in Figure 1, where the follower is in contact with the rear wall 7 of the cabinet before the towels are placed on the supporting rod, the rear wall having a recess 31 formed therein to receive the hand of the attendant if he wishes to grasp the upper edge of the follower. The rod 18 connects the upper portions of the bars 15 and holds them in parallel relation. When the treadle 20 is depressed, the links 23 and 24 of the toggle will be opened as indicated in Figure 2, the lower portion of the arms 15 will be swung inwardly or backwardly against the tension of the springs 25 and the upper portions of said arms will be swung forwardly with the follower supported thereon. The attendant by keeping one foot on the treadle, can hold the follower out of contact with the bundle of towels. As soon, however, as the treadle is released, the tension of the springs will swing the supporting bars and move the follower inwardly or backwardly, causing it to press with considerable force against the forward towel of the bundle.

In the operation of the cabinet, the user depressing the treadle can conveniently withdraw a towel from the bundle and pull it forward to a position where it can be conveniently used. As he leaves the cabinet, release of the treadle will release the follower and it will immediately return to its normal position to exert a yielding pressure on the bundle of towels.

The cabinet as shown is preferably made of angle bar material to insure rigidity and a minimum of weight and the moving parts are protected in their guides so that it will be practically impossible for any of them to become bent or twisted, and prevent the successful operation of the cabinet. The follow-

er plate being loosely mounted, is free to swing on its pivots and adjust itself to the face of the bundle of towels as the bundle is reduced in size by the withdrawal of the forward towel.

It will be understood in the structure of this cabinet that an equivalent mechanical device may be substituted for the springs shown and described, and hence I do not in this application wish to be confined to the specific tension means shown herein, and in various other ways the details of construction herein shown and described may be modified and still be within the scope of my invention.

I claim as my invention:

1. An individual towel cabinet comprising a frame, a horizontal support in the upper portion of said frame whereon a number of individual towels are suspended, a follower plate for engaging and pressing the towels backwardly in said frame, a spring connected with and normally urging said follower against the towels, toggle links operatively connected with said plate, and means for operating said links to move said plate outwardly and relieve its pressure on the towels.

2. A towel cabinet comprising a frame, a horizontal rod adapted to support a bundle of individual towels, one in front of the other, a follower plate adapted to bear on the bundle of towels, a toggle mechanism having means connecting it, connecting said treadle with said follower plate, a treadle operatively connected with said toggle mechanism, and means normally resisting the depression of said treadle and the outward movement of said follower away from the towels.

3. A towel cabinet comprising a frame, a support for a bundle of individual towels placed one in front of the other thereon, a follower plate adapted to bear on the bundle of towels, upright pivoted bars whereon said follower plate is supported, a treadle device, means pivotally connecting said treadle device with said bars, and means connected with said bars and adapted to normally hold said follower plate against the bundle of towels with a yielding pressure.

4. A towel cabinet comprising a frame having side angle bars, a support in the upper portion of the cabinet adapted to receive individual towels, arms pivoted in the upper portion of the cabinet and having a limited oscillating movement in slots provided in said angle bars, a follower plate pivotally supported by said bars, means connected with said bars and normally tending to hold their upper ends backward with a yielding pressure, and mechanism for oscillating said bars against the pull of said means to temporarily relieve the pressure on the towels.

5. A towel cabinet comprising a frame, a support in the upper portion thereof adapted to receive a bundle of individual towels, piv-

oted bars mounted in said frame, a follower plate carried by said bars and adapted to bear on the bundle of towels, links pivotally connected to one another and pivoted respectively to said frame and to the lower portion of said bars and forming toggles, springs normally tending to hold said links in a folded position and said follower against the towels with a yielding pressure, a treadle, and means pivotally connecting said treadle with the connected ends of said toggle links, whereby depression of said treadle will cause the toggles to actuate said bars against the tension of said springs and move said follower away from the towel.

6. A towel cabinet comprising a frame, a support whereon the bundle of individual towels may be placed one in front of the other, a follower adapted to bear on the bundle of towels, toggle links having means connecting them with said follower, means adapted to be actuated by the user of the cabinet for operating said toggle links to move said follower away from the towels and release pressure on the forward towel, and means for normally holding the follower against the towels with a yielding pressure.

7. A towel cabinet comprising a frame, a support therein adapted to receive a bundle of individual towels placed one in front of the other, a follower adapted to engage the bundle of towels, oscillatable bars whereon said follower is supported, means connected with said bars and normally urging said follower against the towels with a yielding pressure, and a foot treadle having an operative connection with said bars and whereby said follower plate may be moved away from the towels to permit an attendant to use both hands in placing a fresh bundle of towels in the cabinet.

In witness whereof, I have hereunto set my hand this 27th day of June, 1928.

FRANK G. STEINER.
